US00D824970S

(12) **United States Design Patent** (10) **Patent No.:** **US D824,970 S**
(45) **Date of Patent:** **** Aug. 7, 2018**

(54) **CERAMIC BONDING TOOL WITH
TEXTURED TIP**

(71) Applicant: **COORSTEK, INC.**, Golden, CO (US)

(72) Inventors: **Cesar Alfaro**, Lewisville, TX (US);
Russell Bell, Ventura, CA (US); **Anne Cenedella**, Evergreen, CO (US); **Steve Govorchin**, Superior, CO (US); **Mark S. Greenwell**, Ventura, CA (US); **Brian Seegmiller**, Arvada, CO (US); **Matthew Simpson**, Evergreen, CO (US)

(73) Assignee: **CoorsTek, Inc.**, Golden, CO (US)

(**) Term: **15 Years**

(21) Appl. No.: **29/612,581**

(22) Filed: **Aug. 2, 2017**

Related U.S. Application Data

(62) Division of application No. 29/516,523, filed on Feb. 3, 2015, now Pat. No. Des. 797,171.

(57) **CLAIM**

The ornamental design for a ceramic bonding tool with textured tip, as shown and described.

DESCRIPTION

FIG. 1 depicts a perspective view of a ceramic bonding tool with textured tip.

FIG. 2 depicts a side elevation view of the ceramic bonding tool with textured tip of FIG. 1.

FIG. 3 depicts a top plan view of the ceramic bonding tool with textured tip of FIG. 1.

FIG. 4 depicts a bottom plan view of the ceramic bonding tool with textured tip of FIG. 1.

FIG. 5 depicts a detailed bottom plan view of the ceramic bonding tool with textured tip shown in FIG. 4; and, FIG. 6 depicts a detailed side cross-section view of the ceramic bonding tool with textured tip, the cross-section taken along cross-section indicator line 6-6 of FIG. 5.

The broken lines in the drawings illustrate environmental structure on the article and form no part of the claimed design.
